UNITED STATES PATENT OFFICE.

EDWARD OGDEN TINSLEY, OF NEW YORK, N. Y., ASSIGNOR TO ROBERT GAIR COMPANY, OF NEW YORK, N. Y., A CORPORATION OF NEW YORK.

COLLAPSIBLE DISPLAY CONTAINER WITH AUTOMATIC LOCK.

Application filed August 28, 1926. Serial No. 132,214.

My present invention relates to an improvement in counter display devices for advertising wares of various kinds and comprises in its essential details of structure a 5 simply made, quickly set-up means whereby the device may be shipped in a perfectly compact flat folded condition in large quantities and may be readily set up with a simple movement.

10 When thus erected, the device becomes very stable and may be mounted on a counter or other suitable place for the display of goods thereon or for advertising in conjunction therewith.

15 One of the advantages of my construction is in that the article as made may be compactly folded or knocked down and when in such condition will be substantially rectangular in form and flat so that large 20 quantities of these devices may be packed for convenience in shipment.

Another advantage of my device relates to the manner in which the article may be assembled and erected, and by a simple form 25 of construction, which is embodied in an automatic locking means the device may be locked, erected, under tension, for display purposes.

Another advantage lies in the construction 30 of my device whereby the blank may be readily cut out in a single operation by well known means, is printable on one face thereof and by the addition of a few simple scores, is ready, immediately, for display 35 purposes.

In the drawings, Fig. 1 shows a preferred form of my device in erected position.

Fig. 2 is a sectional view, taken on the line 2—2 of Fig. 1.

40 Fig. 3 is another outline, of the same construction showing the device in the form of a bottle.

Fig. 4 is another form erected showing the device in the form of a rectangular package such as a cracker package.

45 Fig. 5 is a sectional view, taken on the line 5—5, Fig. 4.

Fig. 6 is a blank layout of the bottle form.

50 Fig. 7 is a rear view showing the device in collapsed condition.

Fig. 8 shows the rear of an erected display, and

Fig. 9 is the device in shipping condition.

By referring to Fig. 6, which is a blank layout of the entire device and is constructed

of cardboard of any suitable thickness, the device comprises substantially, a contoured face or display portion generally denoted by 1 which may be of any suitable contour, such as a head, shoulders and body shown 60 in Fig. 1, a bottle as shown in Figs. 3, 6, 7, 8 and 9 or a simulation of a cracker box as shown in Fig. 4.

On the opposite side of the contoured main or face portion of the device and the 65 modifications are arranged two foldable support pieces 4 and 5 both of which are scored by the lines 6 and 7 so that they may be engageably folded toward one another as indicated in Fig. 7. It will be noted that 70 the support tab 4 is provided with two slots 8—8 which are in opposition to and in registry with two outstanding notched locking tabs 9—9 which are attached to the support tab 5. These tabs 9—9 which are part 75 of the support 5 and are unscored and have the down-hanging short foldable locking flaps 10—10 which are integral with and are scored to the tabs 9 by the scores 11—11 so that these may be hingedly folded up- 80 wardly when they are introduced into the slots 8.

When in the assembly position shown in Fig. 7 these tabs are normally folded back and are held so by the slots 8—8 and when 85 the front face 1 is sprung, the flaps 4 and 5 are brought together as indicated in Fig. 8 whereupon the short, scored tabs 10 spring downwardly, as there shown, thereby forming locking notches 12—12 which engage 90 the lower edges of the slots 8 and thereby lock the face piece 1 in tensioned position as indicated by sectional view, Fig. 2.

By this assembly action it will be noted that the base of the device is formed of the 95 bottom edges of the two flaps 4 and 5 and of the front spring face 5 forming a substantially more or less crescent-like base edge portion upon which the device may stand erect upon a counter for display 100 purposes.

The same formation may be carried in a large number of modifications of the front face 1 such as for instance in Fig. 1 it may have the similitude and in the present instance of a head or figure printed thereon and over the main body of the face 1 and the shoulders S thereof may be draped a shirt, coat or other article of wearing apparel thereby giving the effect of a person 110

wearing a shirt or other article, or the similitudes of these articles may be printed thereon.

In the modified form shown in Fig. 4 the general structure is the same as that described for Figs. 1, 6 and 9, with the exception that a light score 13 may be made down the front face 1 so that when the front face 1 is bent and tensioned at the score it may 10 partake of substantially rectangular form as indicated in the sectional view 5 and this front display face may be printed in the similitude of a cracker box or the like thereby to represent the article so being 15 advertised.

In its essence it will be ascertained that my device consists of a flat blank having four sections comprising a contoured, foldable advertising front transversely scored at 20 any desirable point for folding at some point in its display length, and two automatically locking back support flaps which when in operative position, form, with the lower portion of the face 1, a supporting structure of 25 suitable breadth and stability.

It will also be ascertained that the function of the structure is such that it may be shipped in flat, knocked down rectangular form, without any contour protrusions, and 30 will be readily erected by operating the device along those various score lines so that in either of the face forms shown, the tendency of the front face is to remain under tension thereby straining the automatic locks 35 9—9 and causing the device, when erected, to remain in rigid and upstanding position.

In the operation of the locks from the flat to the erectable positions, it will be noted in Fig. 7 that the flaps 10 are folded upwardly on the score lines 11 and in this flat position they are half introduced into the slots 8 the said flaps 10 being thereby placed under tension and constrained in bent or folded position.

Upon desiring to erect the device, the edges 6 and 7 are squeezed together and this forces the flaps 9, constrained, inwardly and causes the front face 1 to bulge. Immediately the flaps 10 are released from their constrained position, they spring downwardly, thereby engaging the lower portion of the slots 8—8 and under the front face tension are thereby locked and held so until released purposely, for packing, etc., as 55 shown in Fig. 8.

In the folded or knocked down condition, it will be noted that the contoured upper portion 3, which may have any outline, representative of any desired article to be advertised, is folded into and is protected by the substantially rectangular lower body, thereby enabling the shipment of these in bulk, without substantial injury to the contoured upper portion, as shown in Fig. 9.

It should be understood that modifications

and variations of the device may be made without departing from the spirit of the invention or exceeding the scope of the appended claims.

Having thus described my invention, 70 what I claim is:

1. In a foldably formed display device, in combination, a front face portion free on one of its ends and having a contour display portion on its opposite end, a support member foldably connected to each side of said front face member and free on both of its ends and on one side, and locking means consisting of slots on the margin of the free side of one of said members and tabs and flaps on the free side of the other of said members engageable with said slots, the device being foldable for shipment by disposing of the support members so that they lie flat against the rear of the front face portion 85 and in alignment and spaced apart at their free sides by engagement of said tabs and flaps in said slots and disposing the display portion flat against the support member, the device being erected for display by folding the display portion to normal position and bending the front face and display portions outwardly while said members are flatly disposed on the front face portion, so that the front face portion is arcuate in 95 cross-section and brings said members into contact at their free sides and under tension of the bent front face portion, the flaps of said locking means then automatically moving to position for locking the tabs in said 100 slots and the support members in contact at their free sides for maintaining the device in erect display form.

2. In a foldably formed device, in combination, supporting members each having a free side, and means cooperating between the free sides of said members for maintaining members in free-side to free-side relation in the same plane and spaced slightly apart at their free sides when said members are 110 free from tension tending to separate them at their free sides and for automatically locking said members in contact at their free sides when said members are forced into contact at their free sides and subsequently subjected to tension tending to separate them at their free sides.

3. In a foldably formed device, in combination, supporting members each having a free side, and means consisting of slots appurtenant to the free side of one of said members and means appurtenant to the free side of the other of said members and insertible in said slots for maintaining said members in free-side to free-side relation in 125 the same plane and spaced slightly apart at their free sides when said members are free from tension tending to separate them at their free sides and for automatically locking said members in contact at their free 130

- sides when said members are forced into contact at their free sides and subsequently subjected to tensions tending to separate them at their free sides.
- 5 4. A display device formed by folding and including a front face portion, support members foldably connected to front face portion and disposed flat on the front face portion for shipping the device, and means associated with said support members and normally tensioned by said support members when the device is in collapsed position for maintaining the support members connected to each other when disposed flat on the front face portion and for automatically locking the support members in supporting position upon flexure of said front face portion only, when the device is changed from collapsed position to display position.
- 10 5. A display card of the class described comprising a front member, a back consisting of two members, and interlocking means, normally tensioned relative to said back members when the device is in collapsed position, associated with said back members, 25 flexure of said front member only, rendering said interlocking means operative to retain said front member in flexed position.
- 15 6. A display card of the class described comprising a front member, a back consisting of two members, interlocking means on one of said back members normally tensioned by the other back member when the card is in collapsed condition, flexure of said front member only, rendering said interlocking means operative to retain said front member in flexed position. 30 35

Signed at New York in the county of New York and State of New York, this 27th day of August, A. D. 1926.

EDWARD OGDEN TINSLEY.
